The ornamental design for a remotely operated light bulb output controller, as shown and described.

DESCRIPTION

FIG. 1 is a front, top and side perspective view of the remotely operated light bulb output controller embodying the design of the present invention;

FIG. 2 is an elevational elevational view thereof, all elevational views being identical;

FIG. 3 is a top plan view thereof; and,

FIG. 4 is a bottom plan view thereof.

FIG. 1

FIG. 3

FIG. 4

FIG. 2
